United States Patent Office

Des. 197,035
Patented Dec. 3, 1963

197,035

HYDROPLANE

Joseph T. Yeager, Sr., 37 Stevenson Ave.,
Trenton, N.J.

Filed Oct. 5, 1962, Ser. No. 71,998

Term of patent 14 years

(Cl. D71—1)

Des. 197,035

PAGE 2

Fig. 2

Fig. 3

FIGURE 1 is a perspective view of the hydroplane showing my new design;

FIGURE 2 is a top and rear perspective view thereof;
FIGURE 3 is a front end view thereof.

The side opposite that shown in FIGURE 1 is a mirror image of the side shown.

I claim:

The ornamental design for a hydroplane, as shown and described.
